UNITED STATES PATENT OFFICE

JOSEPH SPERLING, OF NEW YORK, N. Y.

EMBROIDERING DEVICE

Application filed June 23, 1930. Serial No. 463,060.

This invention relates to improvements in embroidery needles, being particularly directed to a device, whereby embroidery is carried on through successive penetrations 5 through cloth or other material, upon which the design is to be formed. Broadly, it is an object of this invention to provide an embroidery element, comprising a needle member adjustably positioned within a handle, the depth of the penetration of which needle is controlled by an adjustable guiding means exteriorly disposed with respect to said handle, and through which the needle is adapted to pass.

More specifically, it is an object of this invention to provide an embroidery element, in which a needle is adapted to pass through a limiting member, which limiting member has a series of serrations or notches, 20 which cooperate with a pin, whereby the same may be adjustably positioned with respect to the needle, thereby to limit the degree of penetration of the needle, and at the same time, be of such structural formation as to 25 be readily displaceable with respect to the needle and to the handle carrying both the needle and it.

These and other advantages, capabilities, and features of the invention will appear 30 from the subjoined detail description of one specific embodiment therefor illustrated in the accompanying drawing, in which

Figure 1 is a perspective view showing the device in actual use.

Figure 2 is an enlarged perspective view, partly in section, taken along lines 2—2 of Figure 1, showing the method of application of the same.

Figure 3 is a front view of the device.

Figure 4 is a side elevation, partly in section, taken along lines 4—4 of Figure 3.

Referring to the reference characters in the drawing, numeral 10 represents a strip 5 of material, particularly a piece of cloth, which has a design 11 stamped or marked thereon.

The embroidery device comprises a needle 12, here shown formed of a non-metallic substance, but capable of being formed of

wood, metal, or any other element capable of being drilled.

At one end 13 of the handle, there is bored a groove 14, in which is adapted to pass the needle element 15, comprising a stamped metal piece, having groove 16 therein, through which may pass a thread 17, which thread is maintained in position by means of eyelets 18 and 19 at opposite ends of the needle 15, the said needle being adjustably positioned in the groove by means of threaded member 20, which passes through an aperture 21 in the handle, and has its end contacting with the body of the needle.

The guiding means 22 comprises a stamped metal piece, having a long arm 23 and a short bent portion 24, which bent portion is disposed at an angle of about seventy-five or eighty degrees with respect to the long arm 23, so that the flat surface of the same may 65 form a limiting means for the needle 15 as it passes through the cloth or other material which is carried in the so-called embroidery hoop, although it is not essential that such cloth be carried in a hoop.

The needle 15 passes through aperture 25 formed in the short arm 24, and may be slid into various positions in accordance with the desire of the operator, so as to adjust the depth or the penetration of the stitch.

To provide a further means of adjusting the depth or penetration of the stitch of the device, the long arm 23 has a series of serrations or notches 26 formed therein, which notches cooperate with the bolt member 27 having nut 28 associated therewith, the said bolt passing directly through the body of the handle, and the nut being on one surface thereof. In this manner, it is possible to adjust the position of the guiding means with 80 respect to the needle independently of the needle adjustment, or together with the same, thereby to provide ease in assembly of the device for use on various types of work.

It should be observed that this device is so 85 formed as to comprise few parts, all readily accessible, easily removable, and easily assembled in position for functioning.

It is obvious that various changes and modifications may be made to the details of con-

struction without departing from the general spirit of the invention as set forth in the appended claim.

I claim:

- 5 An embroidering device comprising a handle, a needle adjustably positioned at one end thereof, means for locking said needle in position, a guiding means disposed on the peripheral surface of said handle, said guiding
- 10 means comprising a stamped element having a long and short arm, the short arm being formed integral with and angularly disposed with respect to said long arm, and having an aperture through which said needle
- 15 passes, the short arm serving to limit the penetration of said needle, a series of serrations formed on one side of said guiding means, means passing through said handle and adapted to rest in one of said serrations, said
- 20 last-named means being adapted to be locked to said guiding means at any pre-determined serration, thereby to adjustably position said guiding means with respect to said handle and said needle.

25 JOSEPH SPERLING.
